UNITED STATES PATENT OFFICE.

RALPH J. MOULTON, OF WEYMOUTH HEIGHTS, MASSACHUSETTS, ASSIGNOR TO THE GENERAL FIREPROOFING COMPANY, OF YOUNGSTOWN, OHIO, A CORPORATION OF OHIO.

DOOR MOUNTING FOR SAFES AND THE LIKE.

Application filed February 21, 1922. Serial No. 538,272.

To all whom it may concern:

Be it known that I, RALPH J. MOULTON, citizen of the United States, residing at Weymouth Heights, in the county of Norfolk and State of Massachusetts, have invented certain new and useful Improvements in Door Mountings for Safes and the like, of which the following is a specification.

This invention relates to a novel door 10 mounting for safes and safe cabinets whereby the door may be shifted to an out of the way position, that is caused to disappear after the safe is opened for use.

In modern offices where space is at a premium, and numerous articles of office furniture are required to complete the working equipment, the door of a safe occupies otherwise valuable space when it is opened to permit access to the contents of the safe. This 20 is particularly true where large safes or safe cabinets are used because when the safe door is swung away from its seat it either projects out into the aisle-way in front of the safe or if moved backward to a position approximately 180° from its closed position usually obstructs the entrance or prevents convenient access to other articles of furniture thereby preventing their free use and otherwise hampering office facilities. Sometimes 30 the character of the office business requires a battery of several safes which must be placed side by side, and the annoyance caused by one door being swung back to cover the doorway of another is a great inconvenience.

Accordingly, the present invention proposes to provide a novel door mounting or carriage whereby it is possible to shift the door rearwardly parallel to one of the sides of the cabinet after it has been opened thereby enabling the door to be conveniently disposed of or stored while the safe is opened and yet at the same time being readily available for closing the safe when desired.

A further and more specific object of the invention is to provide a simple, practical and reliable construction whereby the door may be mounted to be freely manipulated both as to opening and closing and also shifting to an out of the way position.

With the above and other objects in view which will more readily appear as the nature of the invention is better understood, the same consists in the novel construction, com-

bination and arrangement of parts herein-after more fully described, illustrated and claimed. 55

A preferred and practical embodiment of the invention is shown in the accompanying drawings, in which—

Figure 1 is a front elevation of a safe having the present invention applied thereto.

Figure 2 is a side elevation of the safe with the door open in full lines and shifted to its out of the way position in dotted lines.

Figure 3 is a top plan view of the construction shown in Figure 2 on an enlarged scale. 65

Figure 4 is a detail vertical sectional view taken on the line 4—4 of Figure 2.

Figure 5 is a detail vertical section taken on the line 5—5 of Figure 2. 70

Similar reference characters designate corresponding parts throughout the several figures of the drawings.

According to the present invention it is proposed to equip a safe designated generally as S and having the door D, with novel carriage C which provides a combined swinging and sliding mounting for the door whereby it may be rotated on a vertical axis 75 to permit of access to the contents of the safe, and then shifted horizontally at an angle to the plane of the opening or door-way into which the door fits when closed. This carriage is preferably arranged so that the shifting or sliding movement of the door may take place parallel to one of the side walls of the safe thereby to permit the door to move or retreat edgewise from its otherwise projecting relation with reference to 80 the face or front of the safe. 85

In carrying out the invention along the lines above indicated the door D may be provided with the hinges 1 having the relatively extended leaves 2, which, instead of being secured to the face of the cabinet adjacent the door-way, as under ordinary conditions, are secured as indicated at 3 to the carrier bar or post 4 of the carriage C arranged at one side of the door-way to shift parallel 100 with the outer face of the side wall of the cabinet.

The said carrier bar 4 and the suspending hanger device 5 at the upper end thereof constitute the main parts of the shiftable 105 carriage C, and while the hanger may be of

any suitable and convenient type it may be in the form of a suitable hanger device 5 which may consist of the relatively large I-bolt 6 whose shank portion 7 is provided with the clamping nuts 8 for engaging with the upper end of the bar as shown in Figure 4. The eye portion of the bolt may receive a journal for the rollers R which have a traveling engagement with the bottom walls 10 of the channels or guide-ways G in the hanger track 9. This hanger track is preferably carried by the anchor plate 10 rigidly secured to the top of the safe S and may be also spaced and secured to the side edge of 15 the top through the medium of the shim 11 or its equivalent.

With the arrangement above described it will be apparent that the carrier bar 4 is suspended from the track 9 by the hanger 20 5 and rollers R and therefore may be freely shifted along the channels G thereof. And, for the purpose of steadyng the carrier bar as it is shifted parallel to the side wall of the cabinet the lower end 12 thereof may be 25 provided with keeper projection 13 adapted to slidably engage with the side walls 14 of the slot or guide-way formed in a lower track member 15. This track member 15 may, like the upper track member 9 be se- 30 cured to the cabinet with the aid of the supporting plate 16 and filler or shim 17 thereby to provide sufficient clearance to compensate for the thickness of the door D when the same is shifted so that it will not interfere with the side wall of the cabinet.

Also, to prevent the canting or skewing of the carrier bar 4 under the weight of the door when it is opened and shifted rearwardly along the side of the cabinet, the 40 lower front edge of the door may be provided with a swivelled supporting caster 18 secured to the door by the strap 19 or its equivalent. This caster continuously bears on the floor or other support upon which the 45 safe rests and relieves the strain which would otherwise be imposed on the hinges as well as the carrier bar due to the weight of the door when it is manipulated away from the door-frame.

50 From the foregoing it is thought that the features and advantages of the present improvement will be readily apparent to those skilled in the art, and while the present drawings and description refer to a simple, 55 and practical embodiment of the invention, it will of course be understood that the primary and underlying feature of providing a disappearing door for a safe or safe cabinet may be embodied in different structural forms without departing from the spirit of the invention or scope of the appended claims.

I claim:—

60 1. A disappearing safe door mounting in- 65 cluding a carriage arranged on the side wall

of the safe and including an upper suspending track and a lower guide track, a vertical carrier bar having a roller hanger at its upper end adapted to ride in the said hanger track and having its lower end guided in 70 the lower track, hinges for connecting the door with the carrier bar, and a caster carried by the swinging end of the door.

2. A disappearing safe door mounting for 75 fire-proof safes including the safe body having a front door opening and provided at one side, outside of its inner compartment, with upper and lower fixed guide members in substantially the same vertical plane, an upright carrier member having at its lower 80 end a slidable holding and guiding engagement with the lower guide member and provided at its upper end with a load-sustaining traveller having a supporting and traveling engagement with the upper guide member, 85 and the safe door carrying hinges mounted on said upright carrier member.

3. A disappearing safe door mounting for 90 fire-proof safes including the safe body provided exteriorly of one side of its inner compartment with an upper track member and with a lower guideway, an upright carrier post having a slidable holding and guiding engagement with the lower guideway, a suspension hanger supported by and having a traveling engagement with the upper track, 95 said hanger having the upper end of the carrier post connected therewith whereby the load assumed by the carrier post is transferred to the hanger, and the door having its hinges secured to the carrier post.

4. A disappearing door construction for 100 safes including the safe body, an upright carrier member having a traveling movement at one side of the safe body from front to rear thereof and vice versa, said upright carrier having a load sustaining suspension at its upper end and a fixed holding guide for its lower end, and the safe door having its hinges fastened to the upright carrier.

5. A disappearing safe door mounting for 110 fire-proof safes including the safe body, an upright carrier having a shiftable movement from the front to the rear and vice versa of the safe body, means for assuming and sustaining the load imposed on the carrier, and the door having its hinges fastened to said carrier.

6. A disappearing safe door mounting for 120 fire-proof safes including the safe body, an upright carrier having a shiftable movement from the front to the rear and vice versa of the safe body, means for assuming and sustaining the load imposed on the carrier, and the door carrying the door hinges, 125 said hinges being provided with arms or leaves at least equal in length to the distance between the carrier and the nearest edge of the door opening and fastened to the carrier.

7. A disappearing safe door construction 130

for safes including a safe body having a front door opening and provided at one side with upper and lower guide members, an upright carrier having a shiftable movement from the front to the rear and vice versa of said body, one end of the said carrier having a holding and guiding engagement with one of said guides and the other end of said carrier provided with a traveler engaging the other of said guides, and the door having 10 its hinges connected with the said carrier.

5 In testimony whereof I hereunto affix my signature in the presence of two witnesses.
